UNITED STATES PATENT OFFICE.

THOMAS H. MEUSHAW AND CONRAD J. DIEZ, OF BALTIMORE, MARYLAND.

FIRE-PLUG.

1,351,781.

Specification of Letters Patent.

Patented Sept. 7, 1920.

Application filed September 11, 1919. Serial No. 323,063.

To all whom it may concern:

Be it known that we, THOMAS H. MEUSHAW and CONRAD J. DIEZ, citizens of the United States, residents of Baltimore, Maryland, have invented certain new and useful Improvements in Fire-Plugs, of which the following is a specification.

Our invention relates to an improvement in fire plugs and is designed to provide an attachment which may be carried with the pumping apparatus and connected up with the ordinary fire plug, this attachment comprising a head, carrying a pipe connection to the nozzle, a suction connection to the pumper and a return pipe connection under pump pressure to the nozzle, valves also being provided, whereby the ordinary pressure in the main may be utilized or the pressure of the pumper.

Our invention also includes a modification which may be permanently connected to the fire plug and utilized to deliver water under the main pressure or through the added pressure of the pumper.

In the accompanying drawings:—

Figure 1 shows in diagram the pumper with the connections to the ordinary fire plug, this view showing the complete connection adapted to be carried by the pumper.

Fig. 2 is a detailed view of the connecting head interposed between the pipes leading to and from the pumper and the fire plug.

Fig. 2^a is a detailed view showing the three-way valve permitting the utilization of either the ordinary main pressure or the pressure through the pumper.

Fig. 2^b is a sectional view showing the form of valve, taken on line b—b of Fig. 2^a.

Fig. 3 is a sectional view showing the gate valves for controlling the flow to the pumper.

Fig. 4 is an enlarged view of the head and associated parts.

Fig. 4^a is a detailed view of the gate valve.

Figs. 5 to 8 show the modified form of the device adapted to be permanently applied to the fire plug.

In Fig. 1 the fire plug is shown at A and the head at B, this head having pipe connections to the pumper so as to direct the water through the pumper to the discharge nozzle also carried by the head B, this head being the supporting medium for the three pipes and also connecting with the fire plug, and in the form of the invention shown in Fig. 1 it is carried by the pumper as a complete connection and is adapted to be fitted

to the ordinary fire plug when in use. This head has a section b, as shown in Fig. 2, which in turn has at one end a coupling b', adapted to be screwed upon the threaded exit pipe of the fire plug, while at its opposite end it is screw threaded, as at c, where it is adapted to receive the threaded end of the suction hose leading to the pumper shown at d. A gate valve e operated in the usual manner by a hand wheel f and a threaded stem g, is provided at the rear end of the section b so as to completely close the exit opening to the pumper when it is desired to use the ordinary main pressure which would then pass out through the opening h, Figs. 2 and 3, to the exit nozzle i. When the pumper is in action the water passes through the pipe d through the pumper and is returned through the pipe k to the exit nozzle, 75 a valve m shown in Figs. 2^a and 2^b being actuated through the spindle n to either permit the passage of the water under main pressure direct to the discharge nozzle, or by closing the direct pressure opening h, as in Fig. 2^a, and opening the gate valve e the pressure will pass through the pumper.

In Fig. 4 we show how the pumper may be cut out completely and the plug pressure used through three sets of hose, namely, 85 by putting a reducer o on the end of the section b and connecting an independent hose p thereto and applying a discharge nozzle to each of the hose pipes p, k and i, shown in this figure. The same head b may be utilized 90 without change except as to the reducer o and pipe p.

Instead of carrying the head b with the pumper and as a detachable connection to the plug, it may be permanently attached to 95 the ordinary fire plug by mounting it upon the head of the plug without in any way changing or altering the plug proper as to its ordinary outlets, as shown for instance in Fig. 5 where the plug is indicated at A 100 and the ordinary outlets at 1 and 2.

We utilize the same device so far as the head B is concerned, except that it is directly mounted upon the head of the plug and the opening from the plug into the head B' is through an ordinary valve which is opened or closed through a turning stem g which has a lower end threaded to the valve stem r so that when it is desired to utilize the plug through the addition supported 105 upon the head thereof it is only necessary to open the valve, which allows the water to

pass upward in to the head B'. The water then passes through the opening c', the pumper, and back through the opening k' and thence out through the discharge i' or 5 a reducing coupling may be applied to c' and an independent discharge pipe to k' and the plug pressure used through three independent discharges, as in Fig. 4.

The valve m', shown in Fig. 7, is utilized 10 to cut off the various inlets and allow the water to be directed either through the pumper, or direct from the main chamber of the part B', provided, of course, in this latter event the valve e' taking the place of the gate valve is closed.

What we claim is:

1. A connection for fire plugs comprising a head adapted for connection with the plug, said head having a main pipe for direct connection with the engine, a valve for controlling the flow from said main pipe, 20

two couplings supported from the head, one for the return pipe from the engine, and the other for the outlet to the nozzle, and a three-way valve for closing the outlet 25 from the engine and making a direct connection from the head to the nozzle to cut out the engine or for causing the flow through the engine when the main outlet valve is open, substantially as described.

2. A head adapted to be mounted upon a fire plug, comprising a valved outlet to an engine and two couplings provided with pipes, with a single valve controlling the exit to one pipe from the main source of 35 supply, and also cutting off by the same action the discharge pipe from the engine substantially as described.

In testimony whereof we affix our signatures.

THOMAS H. MEUSHAW.
CONRAD J. DIEZ.
